UNITED STATES PATENT OFFICE

FREDERICK G. SARGENT, OF WESTFORD, MASSACHUSETTS

DEVICE FOR INCREASING BUOYANCY

Application filed September 21, 1928. Serial No. 307,402.

This invention relates to a device for increasing the buoyancy of a machine or the like, particularly for the purpose of assisting in the raising of an aeronautical machine or 5 raising it straight up in the air.

The principal objects of the invention are to provide a power driven device which will create a partial vacuum in such a place that the device will tend to rise and also create 10 a re-action which will further assist in its rising in the air; to provide the device with a recess in which the suction may be created; and to provide as a part thereof a fan in which there will be no loss of air between the 15 blades and the casing and which will be particularly efficient for creating air currents downward to help in lifting the device and can be made strong and durable.

Other objects and advantages of the invention will appear hereinafter.

Reference is to be had to the accompanying drawings, in which

Fig. 1 is a diametrical sectional view of a preferred embodiment of the invention; and 25 Fig. 2 is a sectional view on the line 2—2 of Fig. 1.

In this form the device comprises a casing 10 having an air inlet 11 at the top provided with a regulating damper 12 and a recess 13 20 in the bottom which has no inlet. This recess is located in a hub 14 into which a driving shaft 15 extends.

The fan arrangement consists of a series of 35 curved blades 16 fixed to the casing and to a hub 19 and located in the horizontal part of the chamber within it and also a series of inclined blades 17 located in an annular downwardly extending outlet 18.

When the shaft 15 is turned in the proper 40 direction, the casing will be rotated as a whole and currents of air will be caused to come into the inlet 11 through the fans and out through the outlet 18 which extends all the way around it. Furthermore, a suction will 45 be set up in the space 13 reducing the air pressure on that area so that the atmospheric air pressure on the bottom of the hub will be unbalanced and will tend to raise the device in the air. Of course the air currents coming 50 down through the outlet 18 all around form

a powerful means for raising the device straight upwardly in the air by reaction.

By having the fan blades all fixed to the casing and rotating the casing itself, the loss of air pressure in the spaces between the 55 blades and the casing, where the blades rotate therein, is entirely avoided. Furthermore, the parts are firmly secured together and are not likely to get out of order under heavy usage.

In this way it will be seen that I have provided for taking advantage of two methods of elevation, and that they do not conflict with each other but co-operate to raise the machine to which this is attached directly upwardly 65 in the air.

Although I have illustrated and described only one form of the invention I am aware of the fact that modifications can be made therein by any person skilled in the art without departing from the scope of the invention as expressed in the claims. Therefore, I do not wish to be limited to all the details of construction herein shown and described, but what I do claim is:—

1. In a device for the purpose described, the combination of a rigid casing having a horizontal part provided with a central inlet extending upwardly and an annular vertically downwardly extending outlet around the sides, at the bottom, said casing being rotatable on its own vertical axis and a series of fan blades mounted in stationary position in the horizontal part of the casing and tending to direct currents of air down through the inlet, through the casing, and directly downwardly through the outlet to tend to lift said casing.

2. In a device for the purpose described, the combination of a rigid casing having a horizontal part provided with an inlet extending upwardly and an annular downwardly extending outlet at the sides, a series of fan blades mounted in stationary position in the casing and tending to direct currents of air down through the inlet, through the casing, and directly downwardly through the outlet and a recess in the bottom of the casing at the center which the rotation of the device will tend to exhaust, thus providing un-

balanced pressure at that point and causing the atmospheric pressure on the bottom to assist in raising it.

3. In a device for the purpose described, the combination with a casing and fan blades securely mounted therein, and an outlet from the casing extending directly downward from the bottom all around the circumference, whereby the rotation of the casing will tend to raise the device, of means for rotating the casing, and a recess in the bottom of the casing at the center which the rotation of the device will tend to exhaust, thus providing unbalanced pressure at that point and causing the atmospheric pressure on the bottom to assist in raising it.

4. In a device for the purpose described, the combination of a rigid rotatable casing having a horizontal part provided with a central inlet extending upwardly and an annular vertically downwardly extending outlet at the sides, and a series of fan blades mounted in stationary position in the horizontal part of the casing and tending to induce currents of air through the inlet, through the casing, and directly into the outlet, and a series of fan blades located in said outlet so that when the casing is rotated both sets of blades will produce air currents into and through the outlet.

In testimony whereof I have hereunto affixed my signature.

FREDERICK G. SARGENT.
